[57] CLAIM

The ornamental design for a glass door, as shown and described.

DESCRIPTION

FIG. 1 is a perspective view of a glass door showing my new design;

FIG. 2 is a front elevational view thereof, the rear view of the same being a mirror image of the front view;

FIG. 3 is a right side elevational view thereof, the opposite side being a mirror image of the right side;

FIG. 4 is a top plan view thereof;

FIG. 5 is an enlarged fragmentary view of the upper left corner of the glass door shown in FIG. 2;

FIG. 6 is an enlarged sectional view of the door taken along the line 6—6 of FIG. 5;

FIG. 7 is a perspective view of a second embodiment of a glass door showing my new design; and,

FIG. 8 is a perspective view of a third embodiment of a glass door showing my new design.
